UNITED STATES PATENT OFFICE.

JULIUS WEGNER, OF ASTORIA, NEW YORK.

SHAPING-MACHINE.

1,130,454.

Specification of Letters Patent.

Patented Mar. 2, 1915.

Application filed June 10, 1913. Serial No. 772,759.

To all whom it may concern:

Be it known that I, JULIUS WEGNER, a citizen of the United States, and a resident of Astoria, Queens county, and State of New York, have invented certain new and useful Improvements in Shaping-Machines, of which the following is a description, reference being had to the accompanying drawings, forming a part thereof.

10 My invention relates generally to shaping machines and relates more particularly to molding machines for shaping stones along curved or straight lines to form stone moldings for buildings and the like, although the shaping machine of my invention may be used for dressing curved or straight metal surfaces if desired.

Objects of my invention are effectiveness and accuracy in operation, simplicity of construction, comparative inexpensiveness of manufacture, facility of adjustment for curves of long or short radii or for straight work, nonliability of derangement, and other objects and advantages which will 25 hereinafter appear.

My invention includes means for combining two rectilinear right angular movements in such a way that the resultant relative movements of the tool and the work will 30 produce the desired curves.

More particularly, my invention includes synchronizing connections between a work carrier or work supporting bed and a tool carrier, for controlling their relative movements so as to produce the desired result.

In carrying out my invention I have employed an actuating rod which, because of its function in producing radius curves, I have called a "radius link", and shall so 40 designate this part hereinafter in the description and claims. One end of the radius link is adjustable along a lever, for producing curves of different radii.

Provision is made for producing either 45 concave or convex moldings, and in carrying out my invention I have accomplished this by making connection of the part to be moved, such as the tool carrier to the adjusting lever at either the one side or the 50 other of its fulcrum, according as a concave or convex surface is to be formed or dressed.

My invention also contains other advantageous features of construction and combi-

nations of parts, as will appear from the following description.

I shall now describe the machine embodying my invention illustrated in the accompanying drawings and shall thereafter point out my invention in claims.

Figure 1 is a side elevation of a machine embodying my invention. Fig. 2 is a front elevation of the same. Fig. 3 is a plan. Fig. 4 is an enlarged elevation of the connecting rods and crosshead. Fig. 5 is an enlarged elevation of the tool carriage. Fig. 6 is an enlarged plan of the rock shafts. Fig. 7 is an elevation and side view of an attachment for shaping balusters.

In the machine embodying my invention illustrated in the drawings the invention is shown as applied to and combined with the machine which in other respects than modified by my invention is constructed as a usual planer or straight molding machine.

The work is supported on a horizontal work carrier or work-supporting bed 1 above which is hung the tool 2, shown as a rotary tool. The bed 1 is supported by a base 3 provided, as appears in the drawings, with V-shaped guides or ways into which fit guide rails formed on the bed 1. The bed 1 is provided with usual longitudinal T-shaped slots or grooves for use in clamping the work in place. The work-supporting bed 1 is adapted to be reciprocated or fed back and forth longitudinally on the base 3 by usual or any suitable feed mechanism, shown in the drawings as including a feed rack 4 on the under side of the bed 1 engaged by a feed gear 5.

A feed shaft 7 extends transversely of the machine and is connected with the feed gear 5 through a train of reducing gearing shown as a pinion 12 on the end of the feed shaft 95 at the right engaging a gear 11 on an intermediate shaft 6 which is provided with a pinion 10 directly meshing with the feed gear 5. A feed actuating bevel gear 13, fixed on the other end of the feed shaft 7, is adapted to be rotated in either direction by means of bevel pinions 15 and 16 loosely mounted on a short longitudinal counter-shaft 14 and a tooth clutch of ordinary form arranged on the shaft 14 between the pinions so as to rotatively couple either the one or the other of these pinions with the counter shaft 14, so that the feed shaft 7

may be rotated to either direction for correspondingly feeding the work-supporting table longitudinally in one direction or the other. When the clutch is in the middle position shown in the drawings (Fig. 1), it is out of engagement with both pinions and no feeding of the bed 1 will take place. The countershaft 14 carries a bevel gear 17 driven by the bevel pinion 18 from a short shaft shown as coupled by means of step pulleys 19 and 20 and a connecting belt 21 with a main feed shaft 22 journaled on the upper part of a main frame 23 and adapted to be driven from any source of power by a belt pulley 24.

15. The rotary tool is fixed on a horizontal sleeve 25 journaled in bearings or journal boxes on a tool carriage 26 provided, as shown, with gibbs engaging guide-ways on a cross-frame 27, to permit lateral adjustment of the tool carriage 26 and tool 2 carried thereby. The journal boxes 26^a and 26^b on the tool carriage 26 for the tool-carrying sleeve 25 are shown as suitably spaced, the 20 journal box 26^a being movable along the rod 65, its inward movement, however, being limited by the spacing rods 62. The sleeve 25 is shown as screw-threaded, the rotary tool 2 being clamped in position thereon by 25 a nut 28 and intervening spacing or filling washers 29, this arrangement permitting rotary tools of different axial length to be mounted on the tool-carrying sleeve 25, and also in case of a comparatively thin tool, 30 such as the tool 2 shown in the drawings, permits lateral adjustment of the tool along the tool-carrying sleeve 25, relatively to the carriage 26.

35. The rotary tool 2 is adapted to be driven by a tool-driving shaft 30 journaled on the cross-frame 27 and splined to the tool-carrying sleeve 25 so as to impart rotation to this sleeve and to the tool while permitting lateral adjustment of the tool 2 by movement 40 of the tool carriage 26 along the guideways on the cross-frame 27. The tool-driving shaft 30 may be driven from any source of power by means of a belt pulley 31 on the tool-driving shaft 30.

45. To permit the tool, such as 2, to operate on work of different thicknesses or at different heights, and also to provide for feeding the tool 2 down to the work 70, the cross-frame 27, which supports the carriage 26 and tool 2, is vertically adjustable on the main frame 23 by means of lifting screws 32 screw-threaded through the end portions of the cross-frame and journaled at their upper ends in screw-supporting blocks 33 and 50 geared to a screw-actuating shaft 34 also journaled in bearings on the blocks 33. The screw-actuating shaft 34 may be manually rotated to raise or lower the tool 2 by means of a stub-shaft 35, to which the wrench or 55 crank may be applied, shown as connected

60 by sprockets and a sprocket chain 36 to the screw-actuating shaft 34, and journaled in a bearing at the lower end of a vertical supporting bar 37 depending from one of the 65 bearings of the shaft 34 and guided in a bracket 38 on an end of the cross-frame 27.

65. The construction of the machine as so far described is substantially that of an ordinary planer or surfacing machine, but had to be first described in order to properly 70 understand the application thereto and combination therewith of the parts of the machine introduced by my invention and which will now be described.

75. In carrying out my invention, as applied to the planer type of machine illustrated in the drawings, the supporting blocks 33 in which the lifting screws 32 are journaled and supported, are so connected to the work supporting bed 1 that vertical movements 80 will be imparted to the cross-frame 27 through the screws 32, and consequently to the tool carriage 26 and tool 2, in synchronism with the longitudinal movements of the work-supporting bed 1 and at a relative 85 varying ratio and of a relative extent to produce the desired radial curve in vertical planes on the upper surface of the work.

90. A connecting and supporting bar or shaft 95 39 carries the screw-supporting blocks 33 at its ends. The connecting bar 39 is carried by the otherwise free ends of normally horizontal forwardly extending rocker arms 40 and 41 which are fixed at their other ends 100 on a rock shaft 42 journaled at its ends in bearings at the top of the main frame 23. It will now be seen that the mounting of the supporting bar 39 on the rocker arms 40 and 41 provides for vertical movement 105 of the tool 2 independent of and irrespective of the vertical adjustment thereof provided by the lifting screws 32.

110. A sleeve 43 is loosely mounted on the middle portion of the rock shaft 42. The 115 rocker arm 40 and the adjacent end of the sleeve 43 are shown as provided respectively with oval flanges 40^a and 43^a adapted to be rigidly connected together by bolts passing through both flanges, or these flanges may 120 be left unconnected by the removal of the bolts, the latter being the condition illustrated in Figs. 1, 2 and 3. The sleeve 43 is also provided with a rocker arm 43^b which normally extends horizontally rearwardly 125 therefrom. A connecting rod 44 pivotally connects the arm 43^b of the sleeve 43 with a cross-head 45 having a guide stem 46 guided for vertical movement in brackets projecting from the main frame 23, as shown. A 130 second and two-part connecting rod 47 pivotally connects the cross-head 45 with the supporting bar 39. The two parts 47^a and 47^b (Fig. 4) of the connecting rod 47 may be left disconnected from one another, or they 135

may be rigidly joined together by means of oval coupling flanges 47^c and bolts holding the flanges together, the latter being the condition illustrated in the drawings.

5 It will be seen from the foregoing description, in connection with the drawings, that rocking or oscillation of the sleeve 43, with the flanges 40^a and 43^a disconnected and with the flanges 47^c of the connecting 10 rod 47 coupled together, this being the condition shown in the drawings, will alternately raise and lower or vertically reciprocate the tool 2. The mechanical connection is traceable from the sleeve 43 through the 15 rocker arm 43^b, connecting rod 44, cross-head 45 and the connected two-part connecting rod 47 to the supporting bar 39, which may have free substantially vertical movement by reason of the freedom of the rocker 20 arms 40 and 41 and the rock shaft 42, by which the supporting bar 39 will be steadied and guided. It can further be readily understood that if the two parts of the two-part connecting rod 47 be disconnected and 25 the flanges 40^a of the rocker arm 40 and 43^a of the sleeve 43 be coupled together, that rocking or oscillation of the sleeve 43 will communicate vertical reciprocating movements to the tool 2 through the rock shaft 30 42 and rocker arms 40 and 41 keyed thereto and connected directly to the supporting bar 39, the connecting rod 44 and the cross-head 45 then moving idly, but it should be noted however that in this instance the vertical 35 movements of the supporting bar 39 will be in opposite directions, as compared to the direction of oscillation of the sleeve 43, to what they were in the first instance when actuating connection was made 40 through the connecting rod 44 and cross-head 45, as illustrated in the drawings.

A long normally horizontal actuating lever 48 is secured to the sleeve 43 and projects rearwardly over the work-supporting bed 1 45 and base 3, being shown as substantially co-terminous with the latter. A lever-actuating rod or radius link 49 pivotally connects the lever 48 with the work-supporting bed 1. The radius link 49 is shown as made of two 50 parts joined by a turnbuckle 49^a, to provide for longitudinal adjustment of the radius link. The upper end of the radius link 49 is provided with a yoke 49^c partly embracing the lever 48 and pivoted to a pivot block 55 50 adjustable longitudinally of the lever 48 by means of an adjusting screw 51 journaled in the lever, and having, as shown, a squared projecting end portion, for engagement of a wrench or crank handle. The lever 60 48 is provided with a scale 48^a, as shown in Fig. 1, to indicate the point of adjustment of the upper end of the radius link along the lever. The lower end of the radius link 49 is provided with a similar yoke 65 49^b pivoted to a fulcrum block 52 which is

conveniently secured to the work-supporting bed 1 for adjustment longitudinally thereof by means of a T-bolt entering one of the usual longitudinally T-shaped work clamping grooves therein.

In order to reduce the strain on the lever 48, I have provided a counterbalancing arm fixed by a hub 75, as the rock shaft 42 and on which a weight 76 is adjustably mounted and held in place by a screw 77.

It can now be understood that the reciprocatory movements of the work-supporting bed 1 will be translated into vertical movements of the tool 2, through the angular thrust, or pull, as the case may be, of the radius link 49. The arc that would be described by one end of the radius link were it swung about a stationary pivot at its other end will be described on the work in magnified or reduced degree, according to the 80 adjustment of the radius link on the lever 48. In the machine illustrated in the drawings, the lower end of the radius link 49 describes the chord of an arc of which the upper end of the radius link describes substantially 85 the perpendicular. The work, carried by the bed 1, describes the same chord as the lower end of the radius link 49 and the tool describes a reduced or a magnified perpendicular of that described by 90 the upper end of the radius link 49. In some machines, to which this invention is applicable, the main frame, such as 23, carries the tool, such as 2, back and forth over a stationary bed. In such a machine the lower 95 end of the radius rod 49 would remain stationary while the upper end would move in the same arc which, in adjusted degree, would be impressed on the tool, the work being stationary. If, in the machine illustrated in 100 the drawings, the manner of operating the machine is such, as would usually be the case, that the lower end of the radius link is carried past the center line, that is to say, 105 past the perpendicular position of the radius link, the tool 2 will receive two vertical movements in opposite directions for each one-way movement of the bed 1. It is to be noted of my invention that, by reason of the character of the connections between the 110 work-supporting bed or work-carrier 1 and the tool carrier or tool carriage 26, two relatively right angular rectilinear movements are combined to produce the desired curvilinear movements of the tool relatively to 115 the work. It will be noted that the radius link 49 imparts to the tool carrier 26 a rectilinear substantially sine curve vertical movement which, when combined with the rectilinear horizontal movement of the bed 1, gives the desired radial curve to the work. This sine curve movement of the tool carrier of course is not continuous but is incomplete and is interrupted and reversed at 120 each reversal of movement of the bed 1.

130

The tool 2 will either traverse a convex or concave surface on the work as desired, or the machine may be adjusted for straight line work. In the adjustment of the machine illustrated in the drawings, the sleeve 43, to which the actuating lever 48 is secured, is disconnected from the rock shaft 42 and is connected to the supporting bar 39 through the cross-head 45 and connecting rods 44 and 47, as has been hereinbefore noted, so that the tool 2 will be moved in the same direction as the lever 48 and upper end of the radius link 49, and will therefore, act upon a convex surface of the work, for example, for producing an outside molding, such as indicated by the work 70 shown on the bed 1 in Fig. 1. It is readily seen that, in another adjustment of the machine, with the lever 48 directly connected to the rock shaft 42 and with the connection from the cross-head 45 to the supporting bar 39 discontinued, then the tool 2 would be moved in an opposite direction to the lever 48 and upper end of the radius link 49 and would act upon a concave surface of the work, for producing an inside molding, for example.

To adjust the machine for straight line work, for example, for making straight moldings, the sleeve 43 should be fixed on the rock shaft 42, by bolting together the flanges 40^a of the rocker arm 40 and 43^a of the sleeve 43; also bolt together the coupling flanges 47^c of the two-part connecting rod 47, and remove the radius link 49. The double connection thus effected will hold the cross frame 27 rigid on the main frame 23, so that the rotary tool 2 will remain bodily stationary while the work is moved beneath it by the work-supporting bed 1.

The operation of the machine is rendered continuous by means of usual trip dogs 53 longitudinally adjustable along the edge of the bed 1 and adapted to engage and actuate a lever of the reversing clutch 15, hereinbefore described. The lever may of course be manually actuated to stop the feed or to reverse it at any point desired.

In the drawings I have shown an abrasive tool of the rotary type. It is obvious that tools of different character and form could be employed. In Fig. 7, I have shown the machine equipped with an attachment for turning out balusters and the like. The rough piece of work 71 is mounted in a lathe-like structure 61 of the usual form and the work rotated. It is fed up against the tool 2 in the usual manner.

It is obvious that various modifications may be made in the construction shown in the drawings and above particularly described within the principle and scope of my invention.

I claim:

35 1. A shaping machine comprising a work

carrier mounted for rectilinear reciprocating movements, a tool carrier mounted for rectilinear reciprocating movements, substantially at right angles to the movements of the work carrier, and connections between the work carrier and the tool carrier compelling one of these carriers to make a plurality of rectilinear movements in opposite directions while the other makes a single rectilinear movement. 75

2. A shaping machine comprising a work carrier mounted for rectilinear reciprocating movements, a tool carrier mounted for rectilinear reciprocating movements, substantially at right angles to the movements of the work carrier, and connections between the work carrier and the tool carrier for imparting to the tool carrier two opposite rectilinear movements while the work carrier is making one rectilinear movement, 85 the movements of the tool carrier being interrupted substantially sine curve movements as compared to the movements of the work carrier. 85

3. A shaping machine comprising a work carrier and a tool carrier mounted for relative rectilinear reciprocating movements in directions of movement at an angle to each other, and connections between the work carrier and the tool carrier for synchronizing their relative movements, such connections including adjusting means for varying the relative extent of the movements of the carriers. 90

4. A shaping machine comprising a work carrier mounted for rectilinear reciprocating movements, a tool carrier mounted for rectilinear reciprocating movements substantially at right angles to the movements of the work carrier, and connections between the work carrier and the tool carrier compelling one of these carriers to make two opposite rectilinear movements while the other makes a single rectilinear movement, such connections including adjusting means for varying the relative extent of the movements of the carriers. 100

5. A shaping machine comprising a work carrier mounted for rectilinear reciprocating movements, a tool carrier mounted for rectilinear reciprocating movements substantially at right angles to the movements of the work carrier, and movement synchronizing connections between these carriers including a radius link arranged to connect rectilinear movement in one direction with rectilinear movement at right angles thereto. 115

6. A shaping machine comprising a work carrier mounted for rectilinear reciprocating movements, a tool carrier mounted for rectilinear reciprocating movements substantially at right angles to the movements of the work carrier, and movement synchronizing connections between these carriers 120

125

including the radius link and a lever along which one end of the link is adjustable.

7. A shaping machine comprising a work carrier mounted for rectilinear reciprocatory movements, a tool carrier mounted for rectilinear reciprocatory movements substantially at right angles to the movements of the work carrier, and movement synchronizing connections between the work carrier and the tool carrier including a radius link movable past its center line to impart two opposite rectilinear movements to the tool carrier while the work carrier is making a single rectilinear movement.
- 15 8. A shaping machine comprising a work carrier mounted for rectilinear reciprocatory movements, a tool carrier mounted for rectilinear reciprocatory movements substantially at right angles to the movement of the work carrier, and movement synchronizing connections between the work carrier and the tool carrier including a radius link connected at one of its ends to the work carrier and a lever for actuating the tool carrier and to which the other end of the radius link is connected, the work carrier end of the radius link being adapted to be moved from one end of the center line to the other so as to impart to the lever and
- 25 tool carrier two oppositely directed movements for each unidirectional movement of the work carrier.

- 30 9. A shaping machine comprising a reciprocatory work support, a tool carrier mounted for reciprocatory movements substantially at right angles to the movements of the work carrier, a radius link connected at one end to the work support, a lever to which the other end of the radius link is connected, and means for connecting the tool carrier to the lever at one or at the other side of the fulcrum pivot of the lever for imparting reciprocatory movements to the tool carrier from the work support and for determining the relative direction of movement of the tool carrier according to the disposition of the connections relatively to the fulcrum pivot of the lever.

10. A shaping machine comprising a horizontally movable work-supporting bed, a vertically movable tool carrier, a normally horizontal lever extending longitudinally over the bed, a link connecting the bed and lever and adjustable longitudinally of the bed and along the lever a rocker pivoted concentric with the lever and detachably connected thereto to rock therewith in substantial alinement with the lever, a tool-carrier support to which the rocker is connected, a second rocker projecting oppositely to the first from the same concentric center and movable with the lever a cross-head, guides therefor, a connecting rod between the second rocker on the cross-head, and another and disconnectible connecting rod between the cross-head and the tool carrier support.

11. A shaping machine comprising a horizontally movable work-supporting bed, a vertically movable tool carrier, a normally horizontal lever extending longitudinally over the bed, a link connecting the bed and the lever and adjustable longitudinally of the bed and along the lever, and actuating connections between the lever and tool carrier for imparting vertical movements to the latter.

12. A shaping machine comprising a horizontally movable work-supporting bed, a vertically movable tool carrier, a normally horizontal lever extending longitudinally over the bed, a longitudinally adjustable link connecting the bed and the lever and adjustable longitudinally of the bed and along the lever, and actuating connections between the lever and tool carrier for imparting vertical movements to the latter.

In witness whereof I have hereunto affixed my signature in the presence of two witnesses.

JULIUS WEGNER.
